UNITED STATES PATENT OFFICE.

JOHN LAING WELLER, OF ST. CATHERINES, ONTARIO, CANADA.

COMPOSITE VESSEL.

1,331,604.

Specification of Letters Patent.

Patented Feb. 24, 1920.

Application filed July 1, 1918. Serial No. 242,953.

To all whom it may concern:

Be it known that I, JOHN L. WELLER, a subject of the King of Great Britain and Ireland, residing at St. Catherines, in the 5 county of Lincoln, Province of Ontario, Dominion of Canada, have invented certain new and useful Improvements in Composite Vessels, of which the following is a specification, reference being had therein to the 10 accompanying drawing.

This invention relates to the construction of floating structures, such as ships, barges, scows, etc.

It is an object of the invention generally 15 to improve the hull structure, and particularly to form such a structure in an economical manner of concrete or other suitable initially plastic material and wooden elements so assembled that the required 20 strength may be obtained.

It also is an object of the invention to form the hull of such materials and in such manner that certain structural difficulties may be avoided, such, for example, as the 25 use of wooden planking at places where transverse curvature would have to be given thereto.

Another object of the invention is to facilitate the making of a tightly-calked 30 joint between the wooden and molded portions of the hull-skin.

When read in connection with the description herein, the details of construction and arrangement of parts contemplated by the 35 invention will be apparent from the accompanying drawings, forming part hereof, wherein an embodiment of the invention is disclosed, for purposes of illustration, as applied to a barge.

While the disclosures herein now are considered to exemplify a preferable embodiment of the invention, it is to be understood that it is not the intention to be limited necessarily thereto in interpretation of the 40 claims, as modifications and adaptations within the limits of the claims can be made without departing from the nature and spirit of the invention.

Like reference-characters refer to corresponding parts in the views of the drawings, 45 of which—

Figure 1 is a plan view, certain parts being broken away;

Fig. 2 is a side elevation, certain parts 50 being broken away; and

Fig. 3 is a transverse sectional view with parts shown in perspective projection.

The lower portion of the hull includes transverse frame members of molded concrete or other suitable initially plastic material. Each of these members comprises an intermediate portion 5 extending across the bottom of the hull, an upright 6 at each end (which in the embodiment shown is substantially perpendicular to the intermediate 60 portion), and an obliquely-disposed or inclined brace 7 extending from the intermediate portion to a place near the top of each upright, there being on the brace a substantially horizontal shoulder or abutment 8 adjacent to the jointure of the brace and upright. Preferably the uprights extend above the light-draft water-line of the hull.

In the position corresponding to that of the keelson in a vessel of ordinary construction, a longitudinal member 9 connects the transverse frame members, it being, preferably, of the same material as those members and being cast integrally in position therewith.

The outer skin of the vessel at the bottom and up the bilges to a place above the light-draft water-line is molded of concrete or other suitable initially plastic aggregate suitably reinforced and secured to the frame 80 members, as indicated by 10.

The lower portion of the ceiling or inner siding of the vessel on each side is formed of a reinforced slab or wall 11 of concrete or other initially plastic aggregate, covering 90 the slanting or oblique braces 7 and filling the spaces at the shoulders or abutments 8, whereby greater thickness and strength is obtained at those places. A plank floor 12 extends over the intermediate portions of 95 the frame members between the lower edges of the slabs, the floor and slabs forming a substantially hopper-shaped bottom for the hold of the hull.

Wooden timbers 13, disposed in substantially vertical position, overlap at their lower portions the upper portions of the uprights 6, to the sides of which they are secured by bolts 14, the timbers and uprights constituting the side frame members of the 100 hull.

The outer skin of the vessel, above the lower molded part 10, is formed of wooden planking 15, secured to the outside of the timbers 13 in any suitable manner common 110

to ship construction. The upper edge of the molded skin has a straight-line finish in order that a good calking joint may be had between it and the lowermost lines of planking.

- 5 5 A stringer member 16 extends along each side of the hull and is bolted to the upper portions of the timbers. Deck-beams 17 rest on the stringer members and are secured to the timbers, and pairs of transverse girders 18 in similar positions are connected at intervals of the length of the vessel to opposite timbers. A stanchion 19 is bolted amidships in its upper portion to each pair of girders and at its foot it is set into the angle 10 at the intersection of an intermediate portion of a frame member and longitudinal member 9, to which parts it is bolted. The girders also are strengthened by braces 20 extending from frame timbers to the girders, 15 between each pair of which such a brace is bolted. A deck 21 is carried by the deck-beams and girders.

Wooden siding 22 is secured to the inside of the timbers between the upper edges of 25 the slabs 11 and the stringers 16.

Having thus described my invention, what I claim as new, and desire to secure by Letters Patent, is—

1. In a hull, transverse frame members of 30 concrete or the like in the lower part thereof having uprights at their ends, an outer skin molded of concrete or the like extending over the bottom and up the sides of the hull and secured to said frame members, wooden 35 frame members secured to said uprights and extending upwardly therefrom, and planking secured to the outside of said wooden frame members above said molded skin.

2. In a hull, transverse frame members of 40 concrete or the like in the lower part thereof having uprights at their ends, an outer skin molded of concrete or the like extending over the bottom and up the sides of the hull and secured to said frame members, the upper edges of said skin having a straight-line 45 finish, wooden frame members secured to said uprights and extending upwardly therefrom, and planking secured to the outside of said wooden frame members, there being 50 tightly-calked joints between the lowermost planking and the upper edges of said molded skin.

3. In a hull, transverse frame members of concrete or the like in the lower part thereof

having uprights at their ends, an outer skin 55 molded of concrete or the like extending over the bottom and up the sides of the hull and secured to said frame members, wooden frame members secured to said uprights and extending upwardly therefrom, planking secured to the outside of said wooden frame members above said molded skin, a girder secured to two opposite wooden frame members, and a stanchion secured to said girder and to one of said transverse frame members. 60

4. In a hull, transverse frame members of concrete or the like in the lower part thereof having uprights at their ends, a keelson member connecting said frame members, an outer skin molded of concrete or the like extending over the bottom and up the sides of the hull and secured to said frame members, wooden frame members secured to said uprights and extending upwardly therefrom, planking secured to the outside of said wooden frame members above said molded skin, a girder secured to two opposite wooden frame members, and a stanchion secured to said girder and to one of said transverse frame members and the keelson member at 70 the place of intersection thereof. 75

5. In a hull, transverse frame members of concrete or the like comprising an intermediate portion, an upright at each end, and a brace extending from the intermediate 85 portion to a place near the top of each upright, an outer skin of concrete or the like extending over the bottom and up the sides of the hull and secured to said frame members, and an inclined wall molded of concrete or the like supported by the brace portions of said frame members on each side of the hold of the hull. 90

6. In a hull, transverse frame members of concrete or the like comprising an intermediate portion, an upright at each end, and an inclined brace extending from the intermediate portion to each upright, an abutment near the top of each brace, an outer skin extending over the bottom and up the 100 sides of the hull, and an inclined wall of molded concrete or the like supported by the braces on each side of the hull filling the spaces at the abutments and thereby being anchored thereto. 105

In testimony whereof I affix my signature.

JOHN LAING WELLER.
